United States Patent Office.

F. L. A. M. SMITH, OF BROOKLYN, NEW YORK.

Letters Patent No. 79,018, dated June 16, 1868; antedated June 4, 1868.

OVEN-RACK FOR SHIP-STOVES.

The Schedule referred to in these Letters Patent and making part of the same.

TO ALL WHOM IT MAY CONCERN:

Be it known that I, F. L. A. M. SMITH, of Brooklyn, in the county of Kings, and State of New York, have invented a new and improved Oven-Attachment; and I do hereby declare that the following is a full, clear, and exact description thereof, which will enable others skilled in the art to make and use the same, reference being had to the accompanying drawings, forming a part of this specification.

This invention relates to a new and useful device to be placed in the ovens of ships' stoves or "caboosees," for the purpose of admitting of the dish containing the meat or other article to be cooked being retained in a horizontal position under the rolling of the ship or vessel.

In the accompanying sheet of drawings—

Figure 1 is a transverse vertical section of my invention, taken in the line *z z*, fig. 2.

Figure 2, a plan or top view of the same.

Similar letters of reference indicate corresponding parts.

A A represent the uprights, which have suitable bases, B B, connected by cross-rods C. To the upper parts of the uprights A A, horizontal bars D are attached, and these bars project from the uprights at equal distances therefrom at the opposite sides, the bars D being parallel with the bases B B of the uprights.

The inner surfaces of the uprights A A are grooved vertically, to receive the journals *a*, of a box, E, in which the meat-pan F is placed, and retained in proper position by rods *b b* passing through the pan. The journals *a a* project at right angles from the ends of the box, near its upper part; and they rest upon pins *c c*, which pass horizontally through the uprights, at a greater or less height, according to the height required for the box, the uprights having a series of holes made through them to admit of this adjustment of the pins.

The device above described is placed in the oven of a ship's stove or "caboose," and it will be seen that the box E, in consequence of being suspended as shown, will maintain a horizontal position under the rolling of the ship, the stove or caboose being placed lengthwise with axis of the ship. The fore-and-aft rolling or pitching of a ship is not of any material consequence, and hence no provision need be made against it; the side rolling is what occasions the difficulty in cooking, and which is fully obviated by my invention.

The bars D D prevent the device from tilting over in the oven, when the box E is elevated considerably between the uprights A A, as shown in fig. 1.

The frame which supports the box E, as well as the box itself, may be constructed of cast iron. The meat-pan F may be of sheet iron.

I am aware that patents have been granted for ships' stoves hung in frames, so that their position will remain unaltered during the rolling of the vessel, but my device may be used with the same advantage in the oven of an ordinary stove.

I claim as new, and desire to secure by Letters Patent—

1. The adjustable box E, containing a meat-pan F, suspended on journals *a*, to uprights A A, all constructed, arranged, and operating substantially as described.

2. The grooved uprights or standards A A, provided with a series of holes, through which a removable pin, *c*, is passed, for sustaining the journals or trunnions *a a*, of box E, substantially as and for the purpose described.

3. The application of the bars D to the frame in which the box E is suspended, to prevent the tilting or tipping over of the frame within the oven, substantially as set forth.

The above specification of my invention signed by me, this 9th day of October, 1867.
